CLAIM

The ornamental design for a razor dispenser, as shown and described.

DESCRIPTION

FIG. 1 is a perspective view of a razor dispenser showing my new design;

FIG. 2 is a top plan view thereof;

FIG. 3 is a right side elevational view thereof, the left side being a mirror image of that shown;

FIG. 4 is a front elevational view thereof;

FIG. 5 is a rear elevational view thereof;

FIG. 6 is a vertical cross-sectional view thereof, taken along line 6—6 of FIG. 1; and

FIG. 7 is a bottom plan view thereof.

FIG. 1
